(57) **CLAIM**

The ornamental design for a fingernail margin tool, as shown and described.

DESCRIPTION

FIG. 1 is a perspective view of a fingernail margin tool showing my new design;

FIG. 2 is a front view thereof;

FIG. 3 is a bottom view thereof;

FIG. 4 is a back view thereof;

FIG. 5 is a right-side view thereof, with the fingernail margin tool turned upside down;

FIG. 6 is a top view thereof; and,

FIG. 7 is a left-side view thereof.

The broken line illustration of numbers shown in FIGS. 1 and 6 represents unclaimed portions of the fingernail margin tool, and forms no part of the claimed design.
